UNITED STATES PATENT OFFICE.

CHARLES H. WHITTINGHAM, OF BIRMINGHAM, ENGLAND.

SAFE AND THE LIKE.

Application filed June 4, 1924. Serial No. 717,776.

To all whom it may concern:

Be it known that I, CHARLES HENRY WHITTINGHAM, a subject of the King of Great Britain, residing at Birmingham, in 5 the county of Warwick, England, have invented certain new and useful Improvements in Safes and the like, of which the following is a specification.

This invention relates to safes and the like, and is chiefly designed to provide means whereby a slidable lock bolt may be arranged to control electric alarm circuits so as to give an alarm when any surreptitious or unauthorized attempt is made to 10 tamper with or force the safe. Such an alarm may be raised by an attempt to move the slidable bolt beyond normal fastening position or by a disturbance of the door of the safe when said door is in its closed position.

Referring to the accompanying drawings, Fig. 1 is a vertical longitudinal section through the lock case looking from the front side.

25 Fig. 2 represents a sectional side view of the electrical contact on the inner face of the lock case and the adjacent part of the body of the safe in the closed position.

Fig. 3 is a perspective view of the safe 30 with the door open on a reduced scale.

Anyone having designs against a safe naturally wishes to know if it is in fact locked before seeking to gain access by explosives or by manipulating the combination, for if it be not locked easy access may be had at once. Therefore, the natural and practically automatic first action is to try the bolt before making any move toward blowing or picking. Having this natural 35 first action, the testing out of the bolt, in view and the desirability of sounding an alarm before the safe has been opened rather than afterward, I have provided a construction whereby movement of the locking bolt in the locking direction beyond a predetermined point results in the energizing of a signal.

In carrying the invention into practice, the lock case 1 of the safe door 2 is provided 40 as usual with a slidable door-securing or lock bolt 3 which is adapted to be locked by a key lock 4, the bolt of which enters a recess 5 in the tail of said door-securing or lock bolt.

55 Upon the bolt bar 3^a is an electrical contact 6 which is normally at "break" even

when the bolt has been shot forward for locking purposes, in which position it is shown in the illustration at Fig. 1, the bolt being kept from the extreme forward position by a bow spring 7 or other shaped resilient medium, so that unless the bolt is urged beyond normal locked position, the electrical contact is at "break." From one side of the contact 6 runs an electrical lead 8 which is joined up to the terminal 9 of the electric bell 10 and passes by way of the terminal 11 through the lead 27 to the contact 12 with which the bolt of the key lock 4 is adapted to engage. From the 60 contact 12 the lead 28 is continued to the terminal 13 of the battery 14, and from the terminal 15 thereof the lead 29 passes to the opposite side of the contact 6. The electric bell 10 and the battery 14 are 65 located in recesses formed between the fire-proof filling 16. Conveniently, the electric bell and the battery are mounted upon hinge plates 17 and 18 respectively, for enabling access to them for repair and re- 70 placement.

A separate battery and bell circuit is provided by the lead 27 running from the bell terminal 11 to the key contact 12, thence through the lead 28 to the battery terminal 85 13, and from the battery terminal 15 back through the lead 19 to the bell terminal 20, the circuit being completed when the switch bar 30 is released by the armature of the 80 electromagnet.

With the bolt 3 thrust forward into its fastening position by an operating handle (not shown) applied to the aperture 21, and the lock 4 doubly locked by a two stepped movement of the bolt, the electric 90 circuit is complete except at the contact 6 between which and the sides of the case 1 a small gap is left. Any tampering with the handle will overcome the resistance of the spring 7 and cause the contact 6 to be 100 forced against the sides of the lock case 1 and effect a "make" which will cause the bell to be rung, the battery and bell circuit 19, 27, and 28 remaining closed independently of the contact 6 so that the alarm 105 continues until the safe door has been unlocked. The door-securing bolt 3 can be blocked without the switching on of the circuit at the contact 12 as shown in Fig. 1.

The inside face of the lock case 1 is provided with an electrical contact 22 which 110 is adapted to engage with an abutment 23

on the body of the safe, or any other suitable part thereof. From one side of said contact, the electrical lead 24 runs to the bell terminal 9, and from the bell terminal 11 through the lead 27 and the contact 12 of the key lock 4, from thence to the battery terminal 13, and from the battery terminal 15 through the lead 25 to the opposite side of the contact 22. When the safe door is closed, the contact 22 lies adjacent the abutment 23, or equivalent, such as to leave a narrow gap between them whereby the circuit is kept open. This position may be maintained by a spring 26 of any suitable 15 shape on the front of the safe body or other position between the front face of the body lining and the adjacent inner door plate. Should the door have the slightest inward pressure or be vibrated inwardly such as by 20 tilting or displacing the safe, or by other disturbance, the spring 26 will be overcome and the contact 22 will effect a "make" and close the circuit 19, 27, and 28, and there

will be raised an audible alarm which will continue until the door has been unlocked. 25

It will be obvious that in lieu of a battery and bell alarm, I may employ any other suitable sound alarm, such for instance as a sound horn or hooter, without departing from the spirit of the invention. 30

I claim:

In alarms for safes, a slideable lock-bolt, and yielding resilient means for normally preventing the passage of said bolt beyond a predetermined point, in combination with 35 an alarm circuit and a switch interposed in said circuit, independent of said resilient means, and acting to close the alarm circuit when said lock-bolt is moved beyond said predetermined point against the action of 40 said resilient means.

In testimony whereof, I have signed my name to this specification at Birmingham, England, this 23rd day of May, 1924.

CHARLES H. WHITTINGHAM.
